ANTENNA SYSTEM AND METHOD

Application filed February 21, 1928. Serial No. 255,888.

This invention relates to directional radio signaling and has as an object the obtainment of compactness and simplicity of construction in uni-directional antennæ.

It has been commonly known that under proper operating conditions an antenna system may be given directional characteristics by utilizing two or more antenna conductors spaced apart one half wave length of the oscillatory energy being utilized. One difficulty with systems of this kind is that they occupy a relatively large area and cannot therefore be constructed as a unitary structure. To avoid difficulties in directly supplying oscillatory energy to all of the conductors, antenna systems of this kind when used for transmitting signals have depended largely upon energy absorbed and re-radiated by reflecting antenna conductors spaced a definite distance from the conductors which are coupled to the transmitter. Arrangements of this kind can only approximate a unidirectional effect, since the re-radiated energy is never of the same amplitude as the energy radiated directly from the main antenna conductors.

In accordance with our invention we propose to supply all of the antenna conductors of an antenna system from the same source of energy, and by properly controlling the relative phase angles of the antenna currents, we are enabled to position the antenna conductors within a relatively small space. When utilizing the system for transmitting relatively short wave lengths, say from between 5 to 100 meters, we are able to supply relatively large currents to a very compact unitary antenna structure.

The invention will now be explained in detail in connection with the drawings in which:

Figs. 1, 2, and 3 are circuit diagrams illustrating three different modifications of the invention.

Figs. 4 and 5 are diagrams, illustrating certain principles involved in the invention.

Fig. 6 is a vector diagram illustrating the phase relationship of the currents in the circuits of Fig. 4.

Fig. 7 is a diagram illustrating the mode of operation of Figs. 1 to 3 inclusive.

Fig. 8 is a vector diagram illustrating the phase relationship between the currents in the circuit of Fig. 7.

Fig. 9 is a diagram illustrating the directional characteristics of a system in accordance with the invention.

Fig. 10 is a circuit diagram illustrating a modification of the systems shown in Figs. 1 to 3.

Fig. 11 is a vector diagram illustrating the phase relationship between the currents in different parts of the circuit shown in Fig. 10.

Our invention may be outlined briefly as comprising an antenna structure in which the conductors are all supplied with current from a single source, but in which the phase relationships of the currents are so controlled as to secure substantially unidirectional effect.

Referring to Fig. 1 for a detailed explanation of one embodiment of the invention, we have shown a pair of antenna conductors 11 and 12 which are preferably supplied with oscillatory current from a suitable oscillator 10.

Instead of using two independent conductors we prefer to form these conductors 11 and 12 as opposed portions of a loop, the upper portion of this loop being formed by conductor 13. For tuning the loop to the desired wave length we have shown a variable capacitance 14 connected across the loop end. Connected to conductor 13, preferably at a point approximately midway between conductors 11 and 12, there is a third conductor 16 which is likewise associated with the oscillator 13. Associated with the ends of the loop there is also a reactive balancing arrangement which serves as a means for controlling the current distribution in the loop and which

may conveniently be formed by condenser electrodes 17 between which is disposed the adjustable electrode 18. Electrodes 17 are connected to the loop ends, while the intermediate electrode 18 is preferably connected to some point of neutral potential. Conductor 16 is preferably connected to electrode 18 and thus to a point of neutral potential thru a suitable reactance such as the variable capacitance 19.

10 A variety of signaling circuits may be associated with the antenna. The diagram shows an oscillation generator comprising an electron relay 21 having its plate circuit tuned by means of an inductance 22. For telegraphic signaling, the generation of oscillations may be controlled by means of a key 23 inserted in the current supply circuit for the plate of relay 21. Suitable high 15 frequency chokes 24 are preferably utilized upon both positive and negative terminals of the battery 26 or other source of plate potential. The grid of relay 1 is connected to the filament or cathode thru a suitable leak 27, and one terminal of the inductance 22 is connected to the grid thru a suitable condenser 28. We prefer to provide a loop of such size that the capacitance 14 may be relatively small for tuning the system to a given 20 wave length, and in practice we have secured best results by forming a single loop with a length of wire slightly less than one quarter wave length of the oscillatory energy to be utilized. The particular oscillator circuit which we have shown is desirable where 25 the effective resistance of the loop is relatively low, but where the effective resistance is of a higher value, we can obtain good results by employing an ordinary inductive feed back type of oscillator.

40 The operation of the above system may best be understood from an explanation of certain basic principles involved. Referring to Fig. 4 it will be presumed radiators or antenna conductors A and B are supplied with oscillatory energy from separate oscillators as indicated. It will also be presumed that the oscillators supply currents of equal amplitude and of the same wave length.

45 Referring now to Fig. 5, with respect to some point C which is remote from an antenna comprising conductors at A and B, the phase relationship of currents produced in an antenna at C by waves radiated from conductors at A and B will depend upon the respective times required for energy to travel from points A and B to point C. Assuming for example that A, B and C are in alinement, then the phase relationships between the currents produced at an antenna at C will be determined by the distance d between points A and B.

50 In order to secure the correct phase relationship between the currents in conductors A and B to secure neutralization of energy

in one direction and concentration of energy radiated in the opposite direction, we have discovered and verified the fact that distance d may be made substantially less than one half the wave length of the energy transmitted, provided a certain phase displacement is maintained between the currents supplied to conductors A and B. We have found that the correct phase angle for unidirectional transmission may be expressed as equal to

$$\pi \pm \frac{2\pi d}{\lambda}$$

where d is the distance between the conductors and λ is the wave length of the oscillatory current.

55 Referring to Fig. 6 we have indicated the current I_a in the antenna conductor A, and the current I_b in the antenna conductor B by vectors. When the phase angle between the two currents is adjusted to equal,

$$\pi \pm \frac{2\pi d}{\lambda}$$

60 energy transmitted in the plane of conductors A and B will be concentrated in one direction but substantially neutralized in the other direction. Theoretically the complete characteristic of such a system will be substantially a cardioid.

65 In practice it has been difficult to provide means which will give the correct phase angle for unidirectional characteristics, where both antenna conductors are supplied with energy from a single source. However the system shown in Fig. 1 affords a practical 70 solution of this problem.

75 Referring to Fig. 7, it will be noted that conductor 16 is tapped onto conductor 13 at a point to one side of the center, and that it is connected at its lower end to condenser plate 18, which in practice is not symmetrically located between plates 17. This asymmetrical arrangement is necessary, as otherwise there would be no difference of potential 80 at the ends of conductor 16, and no current would flow therein. To further increase the current in conductor 16, only one side of the loop has been shown connected to the high potential side of the oscillator output, while the other side of the loop is coupled thereto by virtue of its distributed capacitance. A certain control of the current distribution 85 may be had by shifting balancing electrode 18.

90 As the result of the asymmetrical connection of conductor 16 to the loop, current will flow thru conductor 16 and the phase angle of this current may be controlled by the reactance 19. Thus the antenna conductors form an unbalanced bridge circuit and current I_1 , flowing thru conductor 11 divides and a component I_2 flows thru conductor 12 and another component I_3 flows thru conductor 16 and capacitance 19.

We have found that with proper phase relationships existing between currents I_1 , I_2 and I_3 , we can cause the system to have substantially unidirectional effects. Referring to the vector diagram of Fig. 8, it has been found that with a proper phase angle between currents I_2 and I_3 , and with proper proportionality between the magnitudes of these currents, the effective phase angle between currents $I_2 + I_3$ and current I_1 , may be made equal to

$$\pi \pm \frac{2\pi d}{\lambda}$$

15 In this case however d is the distance between the conductor 11 and an imaginary conductor B located at a point intermediate of conductors 12 and 16. In other words the combined effect of currents I_2 and I_3 is equivalent to that of a current flowing in an imaginary conductor B which is substantially equal to I_1 but out of phase by an amount equal to

$$\pi \pm \frac{2\pi d}{\lambda}$$

With the system in this condition, transmission is substantially unidirectional and the characteristic approximates a cardioid. 30 In practice it has been found that a loop of a given size will operate most effectively upon a certain wave length. The best wave length for a particular loop may be determined experimentally. However as explained above we prefer to utilize a conductor for the loop which is slightly less than one quarter wave length in circumference. The distance between conductors 11 and 12 is also preferably equal to about from 40 1/10th to 1/15th of the wave length employed. Shifting of the electrode 18 of the balancing device may be resorted to for securing the desired non-symmetrical current distribution. The magnitude of current I_3 45 may be controlled both by shifting electrode 18 and by varying the capacitance 19.

We have found that the system will operate to secure directional characteristics for various positions of conductor 16 relative to conductors 11 and 12. We prefer however to locate conductor 16 to one side of the center of the loop as shown, since this arrangement renders the system less critical to adjustments. This may be explained by the fact 55 that the imaginary conductor B has proportionally less distance to shift in response to a change in the relative values of currents I_2 and I_3 , than would be the case if conductors 16 and 12 were placed farther apart.

60 Referring to Fig. 9, we have shown curves drawn on polar coordinates which illustrate the characteristics of the system with different adjustments. The polar axis 1 corresponds to the plane of conductors 11 and 12. 65 Curve 2 shows the characteristic of the sys-

tem for proper adjustments of the currents I_1 , I_2 and I_3 . We have found in practice that such a characteristic curve may be approximated when current I_3 is approximately one half the magnitude of current I_2 . Curve 2 approximates a cardioid and represents optimum conditions of operation. Curve 3 illustrates how the characteristics may be varied by an improper adjustment of currents I_2 and I_3 . This curve is no longer a cardioid, but the majority of the energy is still being radiated in one direction. It is interesting to note however that the direction of maximum radiation is shifted to line 4 which is at an angle to the polar axis 1. Thus by adjusting the currents I_2 and I_3 we are enabled in our system to change the directional characteristics and the direction of maximum radiation without physically turning the antenna structure.

85 The system shown in Fig. 2 is essentially the same as that of Fig. 1. In this case however the distribution of current in the loop is adjusted by means of a single variable capacitance 32, and this capacitance also serves to tune the loop to the desired wave length. One side of the loop is still directly connected to the high potential point or to the plate of the oscillator 13 as shown, while capacitance 19 has been shown as connected to the low potential side of the inductance 22. The theoretical operation of the system is substantially the same as that of Fig. 1.

90 In the system of Fig. 3 one side of the capacitance 19, and the balancing electrode 18 have been connected to the ground 33. In this case only one conductor 34 need be provided between one side of the loop and the oscillator generator 13, this conductor being connected to the high potential side of tuned inductance 22. This oscillator also employs a blocking condenser 36 inserted between the plate of relay 21 and the inductance 22.

105 The modification of the invention shown in Fig. 10 is similar to the modifications previously described except that we have shown a current transmission line for transmitting high frequency energy from a remote oscillator to the antenna structure, and this transmission line has been modified to permit rotation of the antenna. In this case we have shown the high potential side of the transmission line, or oscillator, connected to that side of the loop which is nearest to the intermediate conductor 16, rather than the other side as in the preceding forms described. Thus the oscillator has been indicated diagrammatically at 36 and supplies an oscillatory circuit represented by a tuned inductance 37. Tapped upon inductance 37 are the transmission lines 38 which are preferably arranged in parallel relationship. As we propose to permit rotation of the loop relative to the oscillator, we preferably provide a pair of conductors 39 in the form of 110

115 120 125 130

rings which are rotatable together with the loop structure, and which have connections to the transmission lines 38 as my means of brushes 40. Inductance 41 is connected 5 across rings 39 and has a high potential terminal connected to one side of the antenna loop as by means of conductor 42. Conductor 42 preferably connects to that side of the loop formed by conductor 12, while the other 10 side of the loop is coupled by its distributed capacitance represented by the capacitance 43.

In the system of Fig. 10, assuming an upward flow of current in conductor 12, current flow in conductor 16 will be in an opposite direction or downwardly, while the current flow in conductor 11 will likewise be downward. Therefore in order to secure the desired phase relationship to effect unidirectional transmission, the current I_2 flowing in 15 conductor 12 must be greater than current I_1 in conductor 11. The vector diagram for currents in conductors 11, 12 and 16, is shown in Fig. 11. Thus, as there shown, the current I_2 is greater than current I_1 while current I_3 has a phase relationship with respect to current I_2 such as to secure the correct phase angle

$$30: \quad \pi \pm \frac{2\pi d}{\lambda}$$

for the vector quantities I_1 , and $(I_2 + I_3)$. The adjustment of the phase angle, as in the previous forms of the invention, is secured 35 by adjustment of variable capacitance 19. The direction of maximum radiation with this system has been indicated by the arrow.

The conductor rings 39 make up a part of the electrical transmission line between inductances 37 and 41. It is of course necessary 40 for efficient transmission of high frequency energy, that the surge impedance of the line be made equal to the antenna impedance as measured across inductance 41, thus securing the effect of a line of infinite length.

45 It is obvious that our system may be used for both transmission and reception of radio signals and it is to be understood that by "signaling circuit", we have reference to both 50 circuits for generation and reception of radio energy. However the system operates particularly well when transmitting signals upon short wave lengths.

We claim:

55 1. In an antenna system comprising a plurality of parallel conductors lying in a common plane, the method of securing a unidirectional effect at any wave length λ which 60 comprises so adjusting the impedances of some of said conductors with respect to each other and to another of said conductors that currents in said first conductors produce the equivalent radiation effect of a current in an 65 imaginary conductor spaced from said other

conductor by a distance d and differing in phase angle therefrom by

$$\pi \pm \frac{2\pi d}{\lambda}.$$

2. The method of securing uni-directional effects from a radio antenna composed of more than two conductors spaced less than one-quarter wave length apart which comprises so adjusting the reactances of said 75 conductors as to produce the effect of two spaced conductors carrying currents differing in phase by an angle equal to

$$80: \quad \pi \pm \frac{2\pi d}{\lambda},$$

where d is the distance between them and is different from the actual distance between any of the real conductors, and λ is the wave length of the current.

3. The method of securing unidirectional effects from a radio antenna employing a plurality of spaced conductors for effecting an interchange of energy with an absorbing medium, comprising effecting energization of one conductor with oscillatory current of a definite wave length, and producing the effect of an imaginary conductor supplied with oscillatory current of the same wave length but out of phase with the current of the first conductor by an angle substantially

55 equal to $\pi \pm \frac{2\pi d}{\lambda}$, where d is the distance

between the real and imaginary conductors and λ is the wave length of the oscillatory current, said last mentioned effect being produced by supplying oscillatory currents of different phases to said additional real conductors.

100 4. A radio transmitting system comprising a source of oscillatory energy, a plurality of radiating conductors all supplied with energy from said source and spaced apart a distance which is less than one fourth the wave length 105 of the oscillations produced by the source, means for effecting a transfer of energy from said source to said conductors, and means for effecting a phase displacement of the currents in certain of said conductors for effecting substantially unidirectional transmission.

110 5. In a radio system, a source of oscillatory energy, an antenna conductor supplied with current from said source, another antenna conductor spaced from the first conductor and supplied with current from the same source, and means including a third antenna conductor connected in parallel with said other conductors for effecting substantially 115 unidirectional characteristics for the system.

120 6. A directive radio system comprising a conductive loop with a signaling system coupled thereto and a conductor connected effectively in shunt across points of unequal 125

potential in said loop, one end of said conductor being associated with said conductive loop through a reactance element.

7. A radio system comprising a tuned conductive loop, means for effecting non-symmetrical distribution of current in the loop, comprising a conductor connected in parallel across a portion of the loop, and means including a reactance for effecting a flow of current thru said conductor which is out of phase with current in the other parts of the loop, whereby the directional characteristics of the loop are affected.
8. A directive antenna comprising at least three parallel conductors spaced less than one-quarter wave length apart and means for shifting the phase angle of some of said conductors with respect to others whereby there is produced the effect of two parallel conductors carrying currents differing by a

phase angle equal to $\pi \pm \frac{2\pi d}{\lambda}$, where d is the

25 distance between the effective conductors and λ is the wave length of the current.

9. A directive antenna comprising three parallel conductors spaced apart less than one quarter wave length of the exciting energy and connected together at one end, a transmission line connected to the free ends of two of the conductors, and a variable capacity coupling between the free end of the third conductor and the two sides of said transmission line.

35 10. A directive antenna as defined in claim 8, further characterized in this, that a variable condenser is inserted in series in said third conductor.

40 In testimony whereof, we have hereunto set our hands.
